MOTOR DRIVEN SHOE BRUSH

Henry Wedemeyer, Teaneck, N.J.
(1140 Broadway, New York, N.Y.)

Filed Dec. 4, 1963, Ser. No. 77,665

Term of patent 14 years

(Cl. D9—2)

FIG. 1

FIG. 2

FIG. 3

FIG. 4

FIG. 5

FIG. 6

FIGURE 1 is a side perspective view of a motor driven shoe brush, showing my new design;

FIGURE 2 is a top plan view thereof;

FIGURE 3 is a side elevational view thereof;

FIGURE 4 is a bottom plan view thereof;

FIGURE 5 is a front elevational view thereof; and

FIGURE 6 is a rear elevational view thereof.

The side not shown has substantially the same appearance as the side shown, except as indicated in FIGURE 2.

I claim:

The ornamental design for a motor driven shoe brush, as shown and described.
